Application April 20, 1956, Serial No. 579,515

Claims priority, application France April 22, 1955

3 Claims. (Cl. 228—66)

My invention relates to sliding ladders having two or more sections and has for its object to provide a novel hook fitting between the sections, for inclusion in the construction of such ladders.

Known sliding ladders at present utilise for the connection of two sections the one with respect to the other, a stop device known as a "rocker." This rocker is constituted by a locking member pivoted between the two sides of the larger of the two sections in question, which rocker, in the position of use, supports the smaller of the two sections by engaging one of the rungs of this small section. The disengagement of the rocker from the rungs of the small section, to cause this latter to descend with respect to the large section, is effected by giving the operating rope a suitable inclination. This operation is delicate and often dangerous.

This type of rocker has various drawbacks. On the one hand the building of the ladder presents difficulties as the mounting in position of the rocker weakens the sides of the ladder which must carry the spindles for the rocker, further the rocker is rather heavy and, finally, replacement of the rocker necessitates a complete dismantling of the ladder.

Sliding ladders of the "American" type are also known. These ladders comprise fittings constituted by an anchoring member and a release bolt arranged in such manner that, during raising, they automatically engage by their own weight on the successive rungs of the stationary section whilst, in order to disengage the ladder and to lower it, it is sufficient to raise the movable section by about half the spacing between two rungs so that the auxiliary bolt of the fitting engages with the rungs and releases the anchoring member from the successive rungs.

In these so-called American type ladders, the small or sliding section of the ladder is located on the upper side of the large section whereas according to French technique the positions of the sections are reversed.

My invention concerns a fitting derived from the said fitting having an anchoring member and a release bolt which permits the construction of sliding ladders with the movable section located on the under side of the stationary section.

The fitting according to the present invention is formed by a stirrup to be fixed on the movable section of the ladder, this stirrup carrying a spindle on which is mounted to rotate a member having the shape of a comma, the axis of articulation being such that it divides this member into a small arm directed towards the front of the movable section and which constituted the hook for engaging the rungs of the stationary section, and a large arm directed towards the rear, a release bolt, formed by an L piece, being mounted at the extremity of this large arm in such manner that it can turn through a desired angle, so that it is able either to come in the prolongation of this large arm, or to come to bear against the extremity of the small arm to form a closed perimeter, and it is characterised in that the stirrup has a sleeve for mounting on one of the fixed rungs of the movable section of the ladder,

2

the member in the shape of a comma being such that when it is itself supported by its short arm on one of the rungs of the stationary section it also bears on the stirrup mounting rung and exerts on this latter a force tending to hold the movable section pressed against the stationary section.

In order that the invention may be better understood, it will now be described with reference to the accompanying drawings in which:

10 Fig. 1 is a perspective view of a fitting according to the invention.

Fig. 2 is a view in partial section of this fitting in use moving in the ascending direction and passing over a rung of the stationary section.

15 Fig. 3 is a view corresponding to Fig. 2 with the fitting in engaging position on a rung of the stationary section.

Fig. 4 is a view corresponding to Fig. 2 showing the fitting still ascending after passing over a rung of the stationary section.

20 Fig. 5 is a view corresponding to Fig. 2 showing the fitting passing over a rung of the stationary section during the lowering movement.

Fig. 6 is a diagrammatic view of a ladder having three sections showing the disposition of the fittings and ropes 25 in such a ladder.

The fitting represented in Fig. 1 comprises a stirrup 3 having a sleeve 1 and a bore 2 in the sides thereof, the sleeve 1 being fixed on the side of the stirrup which faces towards the inside of the ladder. This stirrup is to be 30 mounted on the rung 4 (shown in position, ready for mounting). It has a spacing reinforcement 5, and at its upper part a lateral lug 6 with an aperture for the passage of a screw or bolt for fixing the stirrup in position. In the sides of the stirrup and at the upper part 35 of this ladder is provided a bore 8 for the engagement of a spindle 9, this spindle being such that it comes flush with the face of the stirrup directed towards the side 10 of the ladder in order not to penetrate into this ladder and not to weaken for this reason the strength of the said side. This spindle preferably has towards its head 11 a threaded portion 12 to cooperate with a corresponding thread provided in the bore 8 of the side of the stirrup 3 directed towards the centre of the ladder.

On this spindle 9 is pivoted a member 13 having the 40 shape of a comma. This member 13 has a small arm 14 directed towards the front of the movable section with respect to the stirrup 3, which small arm has at 15 on its under surface a recess the shape of which corresponds to the cross section of a rung in the stationary section 45 of the ladder. The large arm has in a similar manner at 16 a recess adapted to bear against the back and beneath the rung 4 on which the stirrup 3 is mounted by means of the sleeve 1 and bore 2. At the free extremity 50 of the large arm is formed a fork 17 in which are provided two apertures for a spindle 18 ensuring the mounting for partial rotation of the member forming the bolt 19. This member is constituted by a body with a lug 20 on its inner face, having a bore for the passage of the spindle 18.

55 The fitting, as shown in the drawings, is mounted on the lower rung 4 of the movable section or sections and this fitting is designated, in Fig. 6, by the reference numeral 21. A second similar but "handed" fitting symmetrical with respect to the axis of the section is also 60 mounted on the same rung and applied against the second side of the ladder. In the position of rest shown in Fig. 4, the small arm 14 projects, on the front of the movable section on which it is mounted, sufficiently to come 65 beyond the median plane of the rungs 4' of the stationary section.

When the ladder is raised, and as shown in Fig. 2, the projecting portion of the small arm 14 is pushed back

upon passing by the rung which then comes opposite the fitting and the fitting takes the position shown in Fig. 2. Once the fitting has passed the rung, it takes its position of rest, that is, the position shown in Fig. 4 and if, at this moment, the movable section is allowed to descend, the extremity of the arm 14 co-operating with the rung 4' causes the fitting to rock in a clockwise direction. The fitting then comes into the position shown in Fig. 3, connecting the rungs 4 and 4' and effecting the engagement of the movable section with the stationary section.

On the contrary, if the lowering movement is begun whilst the extremity of the release bolt 19 is located above the rung 4', this bolt, co-operating with the rung 4', pivots around the spindle 18 in a clockwise direction and closes what can be considered as the opening of the fitting as shown in Fig. 5. The movable section will then be able to slide down under the stationary section without engagement of the fitting with the rungs 4'.

In Fig. 6 there has been shown diagrammatically in section a ladder having three sections, the sections being shown separated for clearness.

The section 22 is the stationary section, the section 23 is the movable intermediate section and the section 24 the movable small or third section.

Two fittings 21 such as described are mounted on the lower rung of each of the sections 23 and 24.

A pulley 25 is mounted, by its strap, on the upper rung of the section 22 and a pulley 26 on the lower rung of the section 23, these two pulleys forming the tackle for the single operating rope 27.

The operation of the third section is ensured by a rope 28 which is engaged at one of its extremities with the upper rung of the section 22 and passes over a pulley 29 the strap of which is mounted on the upper rung of the section 23 and the other extremity of which is engaged with the lower rung of the section 24. This rope includes in its length an adjuster 30 for regulating the length thereof so that the sections move proportionately and to ensure an accurate operation of the complete assembly.

It should be observed that what normally would be the lower rung of the movable sections is not fitted, but the position therefor left blank, to avoid the danger presented by a rung in this position when the ladder is in use.

The invention is not limited to the precise forms or details of construction herein described, as these may be varied to suit particular requirements.

What I claim is:

1. A fitting for sliding ladders having two or more sections, comprising a stirrup to be fixed on the movable section of the ladder, this stirrup carrying a spindle on which is mounted to rotate a member having the shape of a comma, the axis of articulation being such that it divides this member into a small arm directed towards the front of the movable section and which constitutes the hook for engaging the rungs of the stationary section, and a large arm directed towards the rear, a release bolt formed by an L piece being mounted at the extremity of this large arm in such manner that it can turn through a desired angle so that it is able either to come in the prolongation of this large arm or to come to bear against the extremity of the small arm to form a closed perimeter, the stirrup having a sleeve for mounting on one of the fixed rungs of the movable section of the ladder, the member of comma shape being such that when it is itself supported by its short arm on one of the rungs of the stationary section it also bears on the stirrup mounting rung and exerts on this latter a force tending to hold the movable section pressed against the stationary section.
2. A fitting as claimed in claim 1 in which one side of the stirrup when mounted in position is adapted to come flat against the inner surface of one "side" of the ladder and which side of the stirrup has an apertured lug adapted to be held by screw means in position against this side of the ladder, and further in which the dimensions of the parts are such that in the position of rest the member of comma shape with the release bolt pivoted thereto hangs so that the short arm of said comma-shaped member projects on the front of the movable section sufficiently to come beyond the median plane of the rungs of the stationary section when in position against the movable section.
3. Fittings for sliding ladders as claimed in claim 1 in which the stirrups are formed "handed," one, of one hand, being mounted on the bottom rung of a movable section of the ladder and attached to one side member of the ladder and the other, of the other hand, being mounted on the same rung and attached to the other side member of the ladder so that the short arms of the comma-shaped members of each fitting project forwardly from the movable section to engage the rungs of the fixed section.
